BY

Paul A. Talbot.
ATTORNEY.

UNITED STATES PATENT OFFICE

106,595

DESIGN FOR A TRIMMING FOR SHOES OR SIMILAR ARTICLES

Frank Hirsch, New York, N. Y.

Application July 16, 1937, Serial No. 70,475

Term of patent 3½ years

To all whom it may concern:

Be it known that I, Frank Hirsch, a citizen of the United States of America, residing in New York city, county of New York, and State of New York, have invented a new, original, and ornamental Design for a Trimming for Shoes or Similar Articles, of which the following is a specification, reference being had to the accompanying drawing, forming part thereof.

Fig. 1 is a plan view, on an enlarged scale, of a trimming for shoes or similar articles, showing my new design.

Fig. 2 is a side view taken at right angle to the disclosure in Fig. 1.

The design unit is contained between the dot and dash lines, which unit is repeated in regular succession as indicated by the extensions beyond the unit boundaries. The stripping is used in the making of shoes or similar articles.

I claim:

The ornamental design for a trimming for shoes or similar articles substantially as shown and described.

FRANK HIRSCH.
